UNITED STATES PATENT OFFICE.

WALTER C. LINDEMANN AND EDWIN A. RUTENBER, OF MILWAUKEE, WISCONSIN, AS-SIGNORS TO A. J. LINDEMANN & HOVERSON COMPANY, OF MILWAUKEE, WISCONSIN, A CORPORATION OF WISCONSIN.

TOASTER.

Application filed October 18, 1923. Serial No. 669,217.

The improvements relate to devices for toasting bread and other articles and more particularly devices of this kind in which an electric heating element is employed. 5 They may be utilized however, for any purpose to which they are adapted.

In devices of this character it is common to provide a carrier for the toast or other article provided with means for causing the reversal of the article when the carrier is moved outwardly and in an upward, downward or sidewise direction, the reversing means usually being connected with the part of the carrier which is movably connected with the frame of the device and also with some other part, so as to operate on the article in connection with the movement of the main carrier so as to cause its reversal; or the carrier is so mounted that it holds the article in a fixed position with respect thereto and is itself reversed. Both these constructions are more or less complex and involve movable connections and the co-operative arrangement of parts, which render the device liable to become broken or get out of adjustment. This is due largely to the fact that toasters and the like are usually operated by unskilled and even careless persons. The objects of the present improvements are among others, to provide means for reversing the article and presenting first one side and then the other to the heating medium without having any movably connected parts included in the reversing means, and to provide an extremely simple and dependable construction for this purpose.

The improvements are illustrated in the accompanying drawings, in which Fig. 1 is a front view of a toaster embodying the improvements with the door in closed position, and partly broken away; Fig. 2 is a plan thereof; Fig. 3 is an end elevation with one door open and the other closed; and Fig. 4 is a vertical cross section of the same, substantially on the line 4-4, of Fig. 1, looking in the direction indicated by the arrows in that figure.

The main frame of the toaster comprises a base 1, upright end portions 2 and 3, and a top or cover 4 supported thereon. The base has a platform that is mounted thereon and extending from side to side, the said platform having downwardly sloping slides,

and supporting the electric heating element 55 5. The upper edge of this element is supported by a bracket 7 dependent from the under side of the top.

On either side of the end frames, and extending across the device from side to side bars 8 and 9 are mounted, and on these bars the outwardly and downwardly opening doors 10 and 11 are hinged. An outwardly and downwardly inclined toaster support 12 is also hinged to each of these 60 bars, preferably by having its outer edge turned around the bar so as to connect it securely, and at the same time permit it to have pivotal movement thereon. The upper and inner edges of these inclined supports 70 rest against the upright bars 13 of the grid between the heating element and the door, the bars 13 being secured to the base and passing through the bracket 7 at the top. The inclination of the outwardly and downwardly inclined support 12 may be varied 75 to adapt it to any particular use, and it may consist of a plate, or of a series of bars, or other construction. The edges of the end members 2 and 3 are formed so that the edge 80 of the support 12 intermediate its ends is outside them. This permits the support to be moved, if desired, by means of a fork or other article insertible between it and the said end bars, even when hot, for the purpose of removing crumbs or oscillating it to cause the article which is being toasted or broiled to slide off on the door, in case it should for any reason fail to slide off by gravity.

It will be noted that the lower edge of the toast is spaced slightly from the bars 13, when in toasting position. This not only prevents it from sticking to the bars, as when buttered toast is being toasted, but causes 95 it to gravitate more readily when the door is opened. The wires or strands 14 of the heating element are closer to each other at the bottom, so that while the toast is spaced more from the element at the bottom, it is 100 subjected to substantially the same heat radiation.

In operation the toast or other article is placed on the door 11 and the door turned upwardly and closed. This brings the article to the position indicated at the left in Figs. 3 and 4, with its lower edge resting on the beveled support 12. When it is desired

to reverse the article, the door is opened, and it will slip out over the outer edge of the support 12 and on the door with the toasted side down, as indicated in Fig. 4. 5 To present the opposite side to the heating element it is now only necessary to close the door again, this movement turning the toast up to its toasting position, with the opposite or untoasted side exposed to the heat.

10 What we claim is:

In a device of the character described, the combination of a grate disposed in a plane approximately parallel with an upright

heating element, of a laterally disposed support for articles to be toasted, such as slices 15 of bread, said support extending outwardly and downwardly, and means for holding the article to be toasted in upright position opposite said grate, said means being disconnected from and operating independently of the said support. 20

Witness our hands this 13th day of October, 1923, at the city of Milwaukee, in the county of Milwaukee, State of Wisconsin.

WALTER C. LINDEMANN.

EDWIN A. RUTENBER.
